ELECTRIC SPRAY GUN FOR SHELLAC,
PAINTS, ETC.Elmer A. Steckel, Jr., and Elmer H. Bridenbaugh,
Denver, Colo.; said Bridenbaugh assignor to
said Steckel

Application September 16, 1935, Serial No. 40,735

9 Claims. (Cl. 299—87)

This invention relates to a sprayer for atomizing and spraying liquids, and is more particularly designed for air brush work with shellacs, varnishes, paints, lacquers, etc. The principal object of the invention is to provide a small, neat, efficient, electrically operated sprayer, in which all blowers, pumps, air hoses, etc., will be eliminated, which will produce its own pressure for atomizing and blowing the fluid; which can be minutely and accurately controlled, operated and used with a single hand; and which can be "plugged" into any convenient electric outlet for instant use.

Another object of the invention is to provide a process for spraying surface coating material in which the pressure for the spraying operation is obtained by volatilizing the solvent of the coating material so that the use of foreign fluids or additional fluids is avoided.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view of the complete invention as it would appear in use.

Fig. 2 is a vertical, longitudinal section therethrough illustrating the operating parts, the section being taken on the line 2—2, Fig. 4.

Fig. 3 is a detail horizontal section taken on the line 3—3, Fig. 4.

Fig. 4 is a lateral section taken on the line 4—4, Fig. 2.

Fig. 5 is a detail enlarged longitudinal section through the spray nozzle and pump head illustrating construction thereof.

Fig. 6 is a side elevation of an alternate form of the invention.

Fig. 7 is a vertical section through the alternate form of Fig. 6.

Fig. 8 illustrates an alternate form of spray nozzle provided with cooling fins.

The invention comprises a generating dome 10 from which two removable jars 11 and 12 are suspended. The jars 11 and 12 are threaded into a cap member 13 which in turn is secured to the bottom of the dome 10 by means of a suitable attachment screw 14 and an attachment bushing 56. The jar 12 is designed to hold the shellac,

paint, or other liquid to be sprayed. The jar 11 contains the solvent or fluid to be vaporized for furnishing the operating pressure, such as alcohol, oil, water, etc.

The liquid is forced from the jar 12 by air pressure furnished by means of an air pump contained within a pump cylinder 15. Within the pump cylinder 15 is a pump piston 16 mounted for limited movement upon a piston rod 17 which extends through the rear of the cylinder 15. The piston rod 17 is moved forwardly, to compress air in the forward end of the cylinder 15, by means of a spring 18 which surrounds the piston rod 17. It is moved rearwardly against the action of the spring 18 by means of a pump handle 19 which is connected through the medium of a pump rod 20 with a yoke 21 clamped on the rear extremity of the piston rod 17. The handle 19 is slidably mounted on the pump cylinder 15 so that it may move freely therealong.

The piston rod 17 is allowed a limited movement in the piston 16 so that on the forward or spring-actuated stroke a valve washer 57 will be forced against a seat 57' on the back of the piston to seal the latter, and on the rearward or manually-actuated stroke the valve washer will move away from the seat 57' on the piston to allow air to flow through the piston to the head of the cylinder.

The compressed air from the front of the cylinder 15 is conducted by means of a conduit 24 into the upper part of the jar 12, to force the paint or other fluid therefrom through a discharge pipe 25. The air also flows from the front of the pump cylinder through a second conduit 26 into the cap at the top of the solvent jar 11, to force the solvent therefrom through a discharge pipe 27.

The forward extremity of the pump is provided with a check valve 28 which is forced against a discharge port 29 by means of a spring 30 to act as a check valve. The air from the pump forces this check valve open and the spring 30 forces it closed to prevent pressure in the jars 11 and 12 from returning air to the pump. The solvent pipe 27 is also protected by a ball check 45 valve 58 to prevent the pressure in the dome 10 from entering the jar 11.

The vaporizing dome 10 is provided with an electrical heating element 31 surrounded by a protecting cap 32. Current is supplied to the element through a suitable conductor 78. The cap in turn is surrounded by a guide sleeve 33. The solvent from the pipe 27 flows into a head chamber 34 in the dome and from thence through the guide sleeve 33 around the hot cap 32. It 55

5 discharges from the extremity of the sleeve 33 in a vaporized condition into the interior of the dome 10. The highly heated and vaporized condition of the solvent creates considerable pressure in the dome 10, and a safety valve 35 is provided to relieve excess or dangerous pressures therefrom.

10 The exit of the vaporized solvent from the dome 10 is controlled by a needle valve 36 which acts to close a valve seat member 37 in the side of the dome 10. A passage 38 leads from the valve seat member 37 to the interior of a spray nozzle shell 39. The spray nozzle shell is clamped in place by means of a clamping bushing 79 so 15 that it may be easily removed for replacement or repairs.

15 The pump cylinder 15 supports a handle frame 22 at the rear of the device from which a suitable hand grip 23 projects downwardly. The 20 needle valve 36 is operated from a trigger 40 positioned on the handle frame 22 convenient to the thumb of the operator. This trigger is connected through a link 41 with an equalizing lever 42, the upper extremity of which is bifurcated 25 to fit over the needle valve 36. A spring sleeve 43 is secured to the needle valve 36 to form a pressure surface for the equalizing lever 42. A compression spring 44 acts to return the needle valve to its seat.

30 The spray nozzle shell 39 is provided with a discharge orifice 45 and encloses an inner member 46. The inner member acts as a stop or seat for the shell 39 to hold the latter in proper 35 ejecting relationship with a passage 47 from which the fluid being sprayed discharges. This relationship creates a vacuum to project the fluid from the pipe 25 through the orifice 45 in the shell 39.

35 The pipe 25 communicates with a feed chamber 48 to the rear of the inner member 46. The flow from the chamber 48 through the nozzle is controlled by means of a second needle valve 49 which acts against a seat in the passage 47. The second needle valve 49 is also operated by 40 the equalizing lever 42 from the trigger 40. A spring sleeve 50 encloses the second needle valve and acts as a pressure surface for the equalizing lever 42 and also as a step for a compression spring 51, which constantly urges the needle 45 valve 49 to its seat.

50 To relieve the pressure in the jars 11 and 12 when desired, a valve rod 53 is provided. This rod extends axially through the hollow piston rod 17 and projects beyond the forward extremity thereof, terminating in a valve washer 54. The valve washer is constantly held against the head of the piston rod by means of a compression spring 55. When the rod 53 is pushed forwardly, its forward extremity will force the 55 check valve 28 from its seat, allowing the pressure in the jars to return through the valve passage 29 and through the hollow piston rod 17 to the atmosphere.

55 Let us assume that the device is to be used for spraying shellac with an alcohol solvent. The alcohol is placed in the jar 11 and liquid shellac is placed in the jar 12. The electrical current is turned into the heating element 31. This current heats the element 31, the enclosing cap 32, and the sleeve 33 to a temperature sufficiently 60 high to vaporize the solvent. The operator holds the device in one hand by means of the grip 23, and with his forefingers pulls the pump handle 19 rearwardly. He then releases the handle, 65 70 allowing the spring 18 to exert a forward pres-

sure on the piston 16. The spring pressure places a predetermined air pressure in the top of both jars 11 and 12. The pressure in the jar 11 forces the solvent into the generating dome where it is immediately vaporized to create vapor 5 pressure in the dome. The pressure in the jar 12 forces the liquid to be sprayed into the feed chamber 48 of the spray nozzle. The operator now presses the trigger 40 with his thumb.

It is desired to call attention to the fact that 10 the link 41 is connected off center on the lever 42 so that a greater leverage is exerted on the needle valve 36 than on the needle valve 49. Therefore the initial pressure on the trigger 40 acts to open the needle valve 36, allowing the 15 high pressure vaporized solvent to flow to the atomizing nozzle. Further pressure in the trigger 40 opens the needle valve 49, allowing the 20 paint or other fluid to be drawn into the vaporizing nozzle and forced therefrom in a fine atomized spray.

25 The amount that the needle valve 36 opens can be regulated by the setting of a stop screw 76 provided with a suitable lock nut 77. The extremity of the screw 76 contacts with the extremity of the needle valve 36 to limit its maximum opening. A similar stop is provided for the needle valve 49 comprising a stop screw 52, the extremity of which acts to contact the rear of the needle valve 49 and limit the maximum opening thereof. If desired, an alternate form of 30 spray nozzle bushing, such as shown in Fig. 8, provided with cooling fins 78, may be provided to cool the nozzle shell 39.

35 It is desired to call attention to the fact that a predetermined pressure in the dome 10 will prevent the spring 18 from forcing fluid past the check valve 28 so that an automatic control is had to prevent excess fluid from reaching the heating element.

40 In Figs. 6 and 7, an alternate form of the invention is shown comprising a frame member 65 supporting a downwardly projecting reservoir 66, which carries the solvent or other pressure-supplying fluid, and also serves as a handle for 45 supporting the device in the hand. The frame member 65 also supports a container 59 for the material to be sprayed and a pressure chamber or vaporizing dome 60.

45 A suction pipe 61 extends downward into the 50 container 59 from a lower atomizing tip 62. A vapor pipe 63 extends from the top of the vaporizing dome to an upper atomizing tip 64.

55 A heating chamber 67 extends downwardly from the vaporizing dome 60 and contains an 55 electrical heating element 68 to which current is fed by means of suitable conductors 69. A pump cylinder 70 is formed in the frame 65 in which a pump piston 71 is reciprocated on the return stroke by means of a manual trigger 72 60 and on the compression stroke by means of a compression spring 73.

65 As the piston 71 moves outwardly, it will draw solvent from the tube 66 through a tube 74 and as it moves forwardly, the spring 73 will force 65 the solvent past a check valve 75 into the heating chamber 67. The element 68 will immediately vaporize this fluid, creating a pressure in the container 60 which will actuate the atomizing tips 62 and 64. In this form of the device there is no 70 control of the vapor pressure to the atomizer. The entire control is accomplished by regulating the amount of solvent pumped to the vaporizing chamber 67.

75 It is desired to call attention to the fact that 75

since a volatile solvent for the material being sprayed is employed as the pressure supplying medium, the material is not harmed in any way. The vaporized solvent forms a perfect solution 5 with the material leaving a perfect, uniform coating after evaporation.

While a specific form of the improvement has been described and illustrated herein, it is desired to be understood that the same may be varied within the scope of the appended claims, without departing from the spirit of the invention. 10

Having thus described the invention, what is claimed and desired secured by Letters Patent 15 is:—

1. A sprayer for spraying a first fluid by vaporizing a second fluid comprising: a generating compartment; a first container for said first fluid; a second container for said second fluid; 20 an electrical heating element in said compartment; an atomizing nozzle; means for conducting said first fluid to said nozzle; means for forcing said second fluid into said compartment so that it will be vaporized by said heating element 25 to create a pressure; and a conduit for conducting the vaporized second fluid from said compartment to said nozzle for spraying said first fluid from said nozzle.

2. A sprayer for spraying a first fluid by vaporizing a second fluid comprising: a generating compartment; a first container for said first fluid; a second container for said second fluid; 30 an electrical heating element in said compartment; an atomizing nozzle; means for conducting a first fluid to said nozzle; and means for forcing said second fluid into said compartment so that it will be vaporized by said heating element to create a pressure; a conduit for conducting the vaporized second fluid from said compartment to said nozzle for atomizing said first fluid at said nozzle; a valve for controlling the discharge of the vaporized second fluid; a 40 second valve for controlling the discharge of said first fluid.

45 3. A sprayer for spraying a first fluid by vaporizing a second fluid comprising: a generating compartment; a first container for said first fluid; a second container for said second fluid; an electrical heating element in said compartment; 50 a spraying nozzle; means for conducting a first fluid to said nozzle; means for forcing said second fluid into said compartment so that it will be vaporized by said heating element to create a pressure; a conduit for conducting the vaporized second fluid from said compartment to said nozzle for spraying said first fluid from said nozzle; a valve for controlling the discharge of the vaporized second fluid; a second valve for controlling the discharge of said first fluid; and a 55 trigger for operating said valves, said trigger being arranged to open said first valve prior to the opening of said second valve.

4. A sprayer for spraying a first fluid by vaporizing a second fluid comprising: a generating compartment; a first container for said first fluid; a second container for said second fluid; an electrical heating element in said compartment; an atomizing nozzle; means for conducting a first fluid to said nozzle; and means for forcing said second fluid into said compartment so that it will be vaporized by said heating element to create a pressure; a conduit for conducting the vaporized second fluid from said compartment to said nozzle for atomizing said first fluid at said nozzle, 70 said means comprising: an air pump; and a con-

duit for conducting the air therefrom to said containers.

5. A sprayer for spraying a first fluid by vaporizing a second fluid comprising: a generating dome; a cap member suspended from said dome; 5 a pair of containers supported from said cap member; an electrical heating element in said dome; an air pump; means for conducting air from said pump to said containers for creating a pressure in said containers; a spray nozzle; a first conduit from one of said containers to said nozzle; a second conduit from the other of said containers to said dome; and a third conduit from said dome to said nozzle so that pressure from the former will actuate the latter. 10

6. A sprayer for spraying a first fluid by vaporizing a second fluid comprising: a generating dome; a cap member supported from said generating dome; a first container for said first fluid supported from said cap member; a second container for said second fluid supported from said cap member; a spray nozzle; a first conduit from said first container to said nozzle; a second conduit from said dome to said nozzle; a third conduit from said second container to said dome; an 20 electrical heating element in said dome; and a manually operated pump for forcing material 25 from said containers.

7. A sprayer for spraying a first fluid by vaporizing a second fluid comprising: a generating dome; a cap member supported from said generating dome; a first container for said first fluid supported from said cap member; a second container for said second fluid supported from said cap member; 30 a spray nozzle; a first conduit from said first container to said nozzle; a second conduit from said dome to said nozzle; a third conduit from said second container to said dome; an electrical heating element in said dome; a pump cylinder projecting rearwardly from said cap member and communicating at its forward extremity with said containers; a hand grip projecting downwardly from the rearward extremity of said pump cylinder; a piston in said cylinder; a spring for forcing said piston forwardly to create a pressure in said containers; a handle adjacent said hand grip for moving said piston rearwardly; and means for controlling the flow through said first and second conduits. 35

8. A sprayer for spraying a first fluid by vaporizing a second fluid comprising: a generating dome; a cap member supported from said generating dome; a first container for said first fluid supported from said cap member; a second container for said second fluid supported from said cap member; a spray nozzle; a first conduit from said first container to said nozzle; a second conduit from said dome to said nozzle; a third conduit from said second container to said dome; an 40 electrical heating element in said dome; a pump cylinder projecting rearwardly from said cap member and communicating at its forward extremity with said containers; a hand grip projecting downwardly from the rearward extremity of said pump cylinder; a piston in said cylinder; a spring for forcing said piston forwardly to create a pressure in said containers; a handle adjacent said hand grip for moving said piston rearwardly; a first needle valve for controlling the flow from said dome through said second conduit; a second needle valve for controlling the flow from said first container through said first conduit, and a trigger mounted adjacent said hand grip for operating said needle valves. 45

9. A sprayer for spraying a first fluid by vaporizing a second fluid comprising: a generating dome; a cap member supported from said generating dome; a first container for said first fluid supported from said cap member; a second container for said second fluid supported from said cap member; a spray nozzle; a first conduit from said first container to said nozzle; a second conduit from said dome to said nozzle; a third conduit from said second container to said dome; an electrical heating element in said dome; a pump cylinder projecting rearwardly from said cap member and communicating at its forward extremity with said containers; a hand grip projecting downwardly from the rearward extremity of said pump cylinder; a piston in said cylinder; a spring for forcing said piston forwardly to create a pressure in said containers; a handle ad-

5 jacent said hand grip for moving said piston rearwardly; a first needle valve for controlling the flow from said dome through said second conduit; a second needle valve for controlling the flow from said first container through said first conduit, said needle valves projecting rearwardly to a position adjacent said hand grip; and a trigger mounted adjacent said hand grip for operating said needle valves; an equalizing lever 10 extending between said rearwardly projecting needle valves; and a link connecting said lever to said trigger, the connecting point of said link being eccentric of said lever so that said first needle valve will open in advance of said second 15 needle valve.
